UNITED STATES PATENT OFFICE.

FRED M. KIDDER, OF WARREN, PENNSYLVANIA.

PINCH BAR.

1,412,007.

Specification of Letters Patent. Patented Apr. 4, 1922.

Application filed April 11, 1921. Serial No. 460,268.

To all whom it may concern:

Be it known that I, FRED M. KIDDER, a citizen of the United States, residing at Warren, in the county of Warren and State of Pennsylvania, have invented new and useful Improvements in Pinch Bars, of which the following is a specification.

This invention relates to an improved pinch-bar for moving railway cars when it is desired to shift them from one location to another as, for example, upon switches and side tracks at railway stations or industrial plants.

The chief objects of my invention are to provide a pinch-bar which is adapted to be applied with equal facility and effectiveness to rails of different dimensions and which is adapted to grip the rail tighter as the force applied thereto for moving the car increases.

Other objects of the invention consisting of novel features of construction and arrangements of parts will become apparent as the description proceeds. The invention is described in connection with the accompanying drawings, in which:—

Figure 1 is a side elevation of the pinch-bar.

Figure 2 is a vertical section on the line 2—2 of Figure 1 looking in the direction of the arrows, and showing the device applied to the T-head of a rail.

Figure 3 is a top plan view of the device.

The numeral 10 designates the body member of the pinch-bar which is provided with a central longitudinal slot 11 in which the lower end of the lever 12 is adapted to operate. The lever 12 intermediate its ends is formed with a boss 13 having an aperture 14 extending therethrough through which extends a pin 15 and the ends of the latter pass through transverse vertical slots 16 formed in the body member 10 and intersecting the longitudinal slot 11 at right angles.

The body member 10 is provided with pairs of spaced lugs 17, 18 between which are inserted the gripping dogs 19, 20 having apertures therein adapted to align with apertures in said lugs 17 and 18 for receiving the pivot pins 21, the latter being retained in place by the heads 22 and the cotter pins 23 which pass through a transverse aperture formed near one end of each pin. The lower ends of the dogs 19 and 20 project below the body member 10 and are provided with recesses for receiving the hardened face plates 24 which are adapted to engage against the

sides of the T-head of the rail when the device is in operative position, as shown in Fig. 2. The hardened face plates are retained in position by means of set screws 25. The dogs 19 and 20 are extended above their pivots 21 and provided with inclined faces 26 which preferably make an angle of about 63° with the horizontal when the face plates 24 are vertical. The pins 15 have rounded ends 27 adapted to engage the inclined faces 26 of the dogs 19 and 20 and thereby form a pivot pin for the lever 12. With this construction it is evident that as the downward pressure on the lever 12 increases, the plates 24 will be forced into tighter contact with the T-head of the rail 28.

In order to release the dogs from their gripping engagement with the rail, when the downward pressure on the operating lever is released, coil springs 29 are provided between the dogs and body member 10 and for this purpose recesses 30 are formed in the dogs to receive one end of the springs and recesses 31 are formed in the body member 80 for partially housing and forming abutments for the other end of these springs.

The vertical longitudinal slot 11 in the body member is terminated at one end by a solid toe piece 33 which is adapted to be inserted under the wheel until it contacts therewith and is provided with a flat bottom surface 34 adapted to slide on top of the rail. The lower end of the lever 12 is forked and a shoe 35 is pivotally connected to the forked extremity by means of the apertured lug 36 of the shoe being inserted therein and pivotally connected thereto by means of a pin 37. The slot 11 terminates at the rear in a solid portion 38 which forms the heel of the body member and this heel is provided with a transverse slot in which is inserted a plate 39 having a knife edge 40 adapted to project beyond the lower surface of the heel and engage the rail head so as to aid in preventing slipping of the body member when pressure is applied thereto. A threaded aperture is formed in the heel 38 and a set screw 41 engaging therein maintains the plate 39 in position. The upper portion of the lever 12 is formed as a socket 42 for receiving a suitable detachable handle to give proper leverage for operating the pinch-bar.

In operation the toe 33 is moved close to the point of contact between the wheel of the car to be moved and the rail with the body member so placed that the flat surface

34 and the knife edge 40 bear upon the T-head of the rail. The springs 29, act to maintain the gripping dogs in released position until a downward force is exerted upon the lever 12. Under these conditions the pin 15 bearing upon the inclined surfaces 26 of the dogs causes the latter to move until the face plates 24 engage the side surfaces of the rail head. It will be noted that the dogs 10 will grip the rail no matter what the dimension thereof may be, in the range of sizes usually encountered in practice, the only effect of the different dimensions of the rails being that the pin 15 will take up a lower 15 or higher position on the surfaces 26 according as the rail head is narrow or wide. Pressure exerted on the lever 12 will tend to urge the dogs more firmly into gripping engagement with the rail and the shoe 35 engaging against the periphery of the wheel of the car will cause the latter to rotate after which the operating lever is raised, the springs 29 release the dogs and the body member 10 may be slid along the top 20 of the rail to a new position when this same action is repeated whereby the car is kept in motion until it is moved the desired distance. Should the body member be left on the rail the car tending to move backward 25 will engage the toe thereof and the knife edge 40 will bite into the rail with sufficient force to prevent rearward motion of the car.

It will be understood that the particular 35 construction described and shown has been chosen for illustrative purposes merely and that the invention as defined by the claims hereunto appended, may be otherwise embodied and applied without departing from 40 the spirit and scope thereof.

Having described my invention what I claim as new and desire to secure by Letters Patent, is:—

1. A pinch bar for moving cars, comprising a body member having a longitudinal slot and transverse vertical slots formed therein, an operating lever adapted to move in said longitudinal slot, rail gripping dogs pivoted to the member for oscillatory movement in said transverse slots, said dogs having inclined upper faces, and a pivot pin for said operating lever passing through said transverse slots and bearing at opposite ends on the inclined faces of said dogs.
- 55 2. A pinch bar for moving cars, comprising a body member having a rail engaging surface, pairs of spaced lugs projecting

from opposite sides of said member, gripping dogs intermediately pivoted in said lugs, spring means for yieldingly holding 60 said dogs in released position, said gripping dogs having inclined upper faces, an operating lever, and a pivot pin for said lever adapted to engage the inclined faces of said dogs whereby said dogs are forced into 65 tighter contact with said rail as the operating pressure on said pin increases.

3. A pinch bar for moving cars, comprising a body member having a rail engaging surface, rail gripping dogs intermediately 70 pivoted on said body member, hardened plates attached to the lower ends of said dogs for engaging the sides of the rail head, said dogs having inclined upper faces, an operating lever, a pivot pin for said operating 75 lever adapted to engage the inclined faces of said dogs whereby said plates are forced into tighter contact with said rail as the pressure on said pin increases, and spring means tending to maintain said dogs 80 in released position.

4. A pinch bar for moving cars, comprising a body member having a longitudinal slot and transverse vertical slots formed therein, an operating lever adapted to move 85 in said longitudinal slot, rail gripping dogs pivoted to the member for oscillatory movement in said transverse slots, said dogs having inclined upper faces and a pivot pin for said operating lever adapted to move 90 vertically in said transverse slots and bear at opposite ends on the inclined faces of said dogs, whereby said dogs may grip rails of different dimensions with equal effectiveness.

5. A pinch bar for moving cars comprising a body member having a longitudinal slot formed therein, the front end of said member having a rail engaging surface, rail gripping dogs intermediately pivoted on 100 said body member, said dogs having inclined upper faces, an operating lever, a shoe pivoted to one end of said lever for engaging a wheel of a car, and a pivot pin for said operating lever adapted to engage the inclined faces of said dogs whereby said dogs are forced into tighter contact with said rail as the operating pressure on the other end of said lever increases.
